UNITED STATES PATENT OFFICE.

F. NOETTE, OF BROOKLYN, NEW YORK.

CUTTING AND DRAWING WIRE.

Specification of Letters Patent No. 15,705, dated September 9, 1856.

To all whom it may concern:

Be it known that I, F. NOETTE, of the city of Brooklyn, in the county of Kings and State of New York, have invented a new and useful Machine for Cutting and Drawing Wire; and I do hereby declare that the following is a full, clear, and exact description of the same, reference being had to the annexed drawings, making a part of this specification, in which—

Figure 1 is a side view of my improvement. Fig. 2, is a plan or top view of ditto. Fig. 3, is an end view of ditto. Fig. 4, is a vertical section of a portion of ditto, X X, 15 Fig. 2, showing the plane of section.

Similar letters of reference indicate corresponding parts in the several figures.

My invention consists in the employment or use of certain devices or parts, constructed, arranged and operating conjointly as will be hereinafter fully shown and described, whereby the wire is cut from a circular metal plate and drawn, as cut, through the usual draw plates by a reel or drum.

25 To enable those skilled in the art to fully understand and construct my invention, I will proceed to describe it.

A, represents a framing having a bed or platform B, on its upper part.

30 C, represents a horizontal shaft which works in suitable bearings in the framing A. This is the driving shaft and has a bevel wheel a, upon it, which wheel gears into a corresponding wheel b, on a shaft D, 35 the shaft D, having a pinion c, on its outer end, which pinion gears into a toothed wheel E, at the side of the framing A, said wheel E, gearing into a wheel F, at one end of a shaft G, which has a circular cutter H, at 40 the opposite end.

On the shaft G and adjoining the wheel F, there is placed a pinion I, which gears into a corresponding pinion J, on a shaft K, which has a circular cutter L, on its end, 45 the edges of the two cutters H L, slightly overlapping each other, as shown clearly in Fig. 3. Each cutter has a roller d, at its side and these rollers bear upon or against a circular metal plate M, from which the wire

50 is cut, (this plate is shown in red) one roller bearing against the upper and the other against the lower side of the plate.

The plate M, is placed upon a vertical spindle N, the upper and lower bearings of 55 which are attached to racks O, O, which are

fitted to horizontal plates P, P, attached to the framing A.

Q, is a vertical shaft having a pinion e, at both ends, which pinions gear into the racks O, O. To the lower end of the shaft 60 Q, a bevel wheel R, is attached. This wheel R, gears into a corresponding wheel S, on a shaft T, which shaft has a ratchet U, upon it, and also a lever V, having a weight f, on its upper end. To the lever V, a pawl g, 65 is attached, said pawl catching into the ratchet V.

To the framing A, an adjustable gage roller h, is attached and the edge of the circular plate M, bears against this roller, 70 which determines the thickness of the wire or the width of the strip which is cut from the plate M, by the circular cutters H, L.

From the above description of parts it will be seen, that when motion is given the 75 shaft C, the two cutters A, L, will be rotated by the gearing, a, b, c, E, F, I, J, and said cutters will cut a strip off from the plate M, the roller h, being so adjusted that the strip may be of the required width, and 80 the edge of the plate being kept against the roller h, by the weighted lever V, pawl and ratchet g, U, racks O, O, and shaft Q, with pinions e upon it, which pinions e gear into said racks; the strip being cut spirally from 85 the periphery to the center of said plate M.

The inner end of the shaft C, has a bevel pinion i, upon it, which pinion gears into a bevel wheel N, on a vertical shaft A'. The wheel N, is placed loosely on the shaft A', 90 and works on a feather j, so that it will turn with its shaft and still be allowed to slide up and down upon it.

The lower end of the shaft A' is stepped in a block B', and has a pinion k, upon it, 95 and through the block B', two screw rods l, l', pass vertically, the lower parts of said screw rods passing through and working in internal screw threads cut in a plate C', attached to the lower part of the framing A. 100 The screw on one rod is cut in a reverse direction to that on the other and the screw rods have pinions a^x, upon them which gear into each other.

On the upper parts of the rods l, l', pinions m, m, are placed one on each rod. These pinions are placed loosely on the rods and fitted on feathers so that the rods may work up and down through them.

To one side of the block B' a lever D', 110

is attached, one end of which is fitted in a vertical slotted bar E' , attached to the framing, the end of the lever being fitted between adjustable bolts n, n , which pass transversely through the slotted bar E' . The lever D' , has a vertical arm F' attached to it at its axis, said arm having a pin o on its upper end, the pin being fitted in a slotted plate p , attached to the end of a horizontal bar G' , which is pivoted to an upright lever H' having a weight q , at its upper end, see Fig. 1.

To the upper end of the shaft A' , a roll or drum I' is attached. This drum is formed of two circular disks r, s , one of which, s , is attached permanently to the shaft and has staves t , attached to it, the lower ends of the staves having beads or cylindrical projections u , upon them which beads fit in an annular groove u' , in the disk, so that the staves may be inclined inward, when the upper disk r , is raised, said disk being placed loosely on the shaft A' , and having an annular groove v , made in it to receive the upper ends of the staves and keep them in proper place. The upper parts of the staves have each a hooked projection w , on their inner sides, in which hooked projections an elastic band x , is fitted to prevent the staves from falling outward when the upper disk r , is raised.

J' , represents draw plates of usual construction which draw plates are fitted within a suitable stock on the bed or platform B . The end of the strip which is cut from the plate M , is attached to the reel or drum I' , which is rotated simultaneously with the plate M , by means of the gearing i, W , and the strip, as it is cut from the plate M , is drawn through the draw plates J' , by the reel or drum I' , said strip being rounded and formed into wire thereby and wound upon the reel or drum.

As the reel or drum rotates, it is raised and lowered gradually, so that the wire may be wound evenly upon it from its lower to

its upper end. This movement of the reel or drum is effected by the gearing below or at the lower end of the shaft A' , the pinions m, m being thrown alternately in and out of gear with the pinion k , by means of the lever D' , which is connected with the pinions m, m , and operated in consequence of the rising and falling of the block B' , in connection with the weighted lever H' and the slotted bar E .

The wire is removed from the reel or drum by raising the upper disk r , thereby allowing the staves to collapse or incline inward. Were this device or construction of the reel or drum not used, it would be extremely difficult to remove the wire from the reel as it is wound tightly around it in consequence of the power required to draw the strip through the draw plates J' .

Having thus described my invention, what I claim as new and desire to secure by Letters Patent, is—

1. I claim feeding the circular plate M to the circular cutters H, L , and gaging the same by means of the racks O, O , shaft Q , with pinions e , attached to the pawl and ratched G, U , weighted lever V , or equivalent, and gage roller h , arranged as herein shown and described.

2. I claim operating the reel or drum I' , or giving it a vertical vibratory movement by means of the right and left screw rods l, l , with pinions m, m , attached and made to gear alternately into the pinion k , on the shaft A' , by means of the block B' lever D' , bar G' , and weighted lever H' arranged as shown and described.

3. I claim the reel or drum I' , when constructed as shown, so that it may be compressed or contracted, to allow of the ready removal of the wire from its periphery.

F. NOETTE.
